FIG 2

INVENTOR.

Patrick H. Moore

UNITED STATES PATENT OFFICE

161,361

MANICURE TABLE

Patrick H. Moore, Los Angeles, Calif.

Application January 20, 1950, Serial No. 7,371

Term of patent 7 years

(Cl. D33—7)

To all whom it may concern:

Be it known that I, Patrick H. Moore, a citizen of the United States, residing at 249 East Vernon Ave., in the city of Los Angeles, State of California, have invented a new, original, and ornamental Design for Manicure Table, of which the following is a specification, reference being had to the accompanying drawing, forming part hereof.

Figure 1 is a view in perspective as viewed from the end of a manicure table embodying my new design;

I claim:

The ornamental design for a manicure table, substantially as shown.

PATRICK H. MOORE.
